UNITED STATES PATENT OFFICE.

HISKIAS MUINONEN, OF NEGAUNEE, MICHIGAN.

TENSION-DEVICE PROTECTOR.

1,333,560.

Specification of Letters Patent.

Patented Mar. 9, 1920.

Application filed May 12, 1919. Serial No. 296,520.

To all whom it may concern:

Be it known that I, HISKIAS MUINONEN, a citizen of the United States, residing at Negaunee, in the county of Marquette and State of Michigan, have invented new and useful Improvements in Tension-Device Protectors, of which the following is a specification.

This invention relates to means for protecting the tension device of a shoe sewing machine from the wax and from the flame for heating the wax pot.

The principal object of the invention is to provide a plate for preventing the flame from reaching the thread at the tension device.

Another object of the invention is to provide means for supporting the tension device a distance above the wax pot to prevent the wax from getting on to the same.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a side view of the wax pot and tension device arranged in accordance with my invention;

Fig. 2 is an edge view;

Fig. 3 is a perspective view of the shield or plate.

In these views 1 indicates the wax pot which is formed in the well known manner and which is secured to the shoe sewing machine in the ordinary way. 2 indicates the tension device which is also formed in the usual manner and which is secured to the

shelf 3 which is formed on the wax pot. In carrying out my invention I locate a block 4 on said shelf on which the tension device rests, the parts being secured together by the screw 5. This block will raise the tension device well above the wax pot so that there is no danger of the wax getting on the tension disk of the tension device.

I also provide a shield 6 for preventing the flame, which heats the wax pot, from burning the thread at the tension device. As shown, this shield is formed of a plate of metal or the like which is provided with a downwardly projecting portion 7 which is to engage the upper inner edge of the wax pot and this part is provided with a hole 8 to receive the screw 9 which connects the wax pot with the machine. The shield is made of sufficient size to fully protect the thread as it passes through the tension device.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

In combination with the wax pot and tension device of a shoe sewing machine, a shelf 75 on said pot upon which the tension device rests, a screw for holding the pot to the machine and a shield having a downwardly extending part provided with an opening 80 for receiving said screw and its other part being flat and extending at right angles from the pot for protecting the thread on the tension device from the heating means for the pot.

In testimony whereof I affix my signature.

HISKIAS MUINONEN.
